(57) **CLAIM**

The ornamental design for a tire shoulder region, as shown and described.

DESCRIPTION

FIG. 1 is a right side perspective view of a shoulder region for a tire showing my new design, it being understood that the shoulder region is repeated throughout the circumference of the tire, the opposite side being the same as that shown;

FIG. 2 is a front elevational view thereof;

FIG. 3 is a side elevational view of the right side thereof, the opposite side being identical thereto; and,

FIG. 4 is an enlarged fragmentary right side perspective view thereof.

The broken lines defining the tire sidewall, inner bead, and the peripheral boundary between the claimed tire shoulder region and the tire are for illustrative purposes only and form no part of the claimed design.
